[57] CLAIM

The ornamental design for a combined trigger sprayer head and material containers, as shown and described.

DESCRIPTION

FIG. 1 is a front, right side perspective view of a combined trigger sprayer unit and material container showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof, on an enlarged scale;

FIG. 7 is a bottom plan view thereof, on an enlarged scale;

FIG. 8 is a front, right side perspective view of an alternate trigger sprayer unit showing my new design;

FIG. 9 is a left side elevational view thereof;

FIG. 10 is a right side elevational view thereof; and,

FIG. 11 is a front elevational view thereof.

The rear elevational view, the top plan view, and the bottom view of the alternative embodiment of FIGS. 8-11 are omitted as being identical to FIGS. 5, 6 and 7 of the first trigger sprayer unit embodiment.

FIG. 1.

FIG. 2.

FIG. 3.

FIG. 4.

FIG. 5.

FIG. 6.

FIG. 7.

FIG. 8.

FIG. 9.

FIG. 10.

FIG. 4.
